Primary Examiner—Louis S. Zarfas*Assistant Examiner*—Catherine R. Oliver*Attorney, Agent, or Firm*—Harry M. Weiss; Jeffrey D. Moy;
Harry M. Weiss & Associates, P.C.[57] **CLAIM**

The ornamental design for a golf glove holder, as shown and described.

DESCRIPTION

FIG. 1 is a perspective view of the golf glove holder showing my new design;

FIG. 2 is a front view thereof;

FIG. 3 is a rear view thereof;

FIG. 4 is a side view thereof, the opposite side being a mirror image;

FIG. 5 is a top view thereof;

FIG. 6 is a front view of an alternative embodiment of the golf glove holder depicted in FIG. 1;

FIG. 7 is a rear view of the embodiment depicted in FIG. 6; and,

FIG. 8 is a side view, the opposite side being a mirror image thereof, of the embodiment depicted in FIG. 6.
